Collender Company, Chicago, Ill., a corporation of Delaware

Application February 2, 1949, Serial No. 625

Term of patent 14 years

(Cl. D34—5)

To all whom it may concern:

Be it known that we, Robert I. Anderson and Bert Hoeker, both citizens of the United States and both residents of the city of Muskegon, in the county of Muskegon, State of Michigan, have jointly invented a new, original, and ornamental Design for a Score Table or the like, of which the following is a specification, reference being had to the accompanying drawings, forming a part thereof, in which:

Fig. 1 is a perspective view, looking at the front of the score table or the like, showing our new design;

Fig. 2 is a front elevational view thereof;

Fig. 3 is a top plan view thereof; and

Fig. 4 is a side elevational view thereof.

The dominant features of the design are shown in full lines.

We claim:
The ornamental design for a score table or the like, as shown and described.

ROBERT I. ANDERSON.
BERT HOEKER.
